(57) **CLAIM**

The ornamental design for a cord holder, as shown and described.

DESCRIPTION

FIG. 1 is a front elevational view of a cord holder of the claimed design,

FIG. 2 is a rear elevational view of the design of FIG. 1; FIG. 3 is a top view of the design of FIG. 1 and the bottom view is a mirror image of the top view;

FIG. 4 is a right side view of the design of FIG. 1 and the left side view is a mirror image of the right side view; FIG. 5 is a cross-sectional view of the design of FIG. 1, taken on section lines 5—5 of FIG. 1;

FIG. 6 is a perspective view of the design of FIG. 1; and, FIG. 7 is a front elevational view of the design of FIG. 1, on a reduced scale in position of use.

The broken lines showing environment in the drawings are for illustrative purposes only and form no part of the claimed design.
